UNITED STATES PATENT OFFICE.

WILLIAM H. GASKILL, OF PHILADELPHIA, PENNSYLVANIA, ASSIGNOR TO
SAMUEL W. EVANS, JR., TRADING AS S. W. EVANS & SON.

UMBRELLA-RUNNER.

SPECIFICATION forming part of Letters Patent No. 778,028, dated December 20, 1904.

Application filed June 8, 1904. Serial No. 211,594.

To all whom it may concern:

Be it known that I, WILLIAM H. GASKILL, a citizen of the United States, residing in the city and county of Philadelphia, State of Pennsylvania, have invented a new and useful Improvement in Umbrella-Runners, of which the following is a specification.

My invention consists of an umbrella-runner provided with means for automatically 10 operating the catch employed in the umbrella-stick for holding said runner in the open condition of the umbrella, whereby said runner is released from said catch and the runner may 15 permit the closing of the umbrella, said means being hereinafter set forth and the novel features thereof pointed out in the claims.

Figure 1 represents a side elevation of an umbrella-runner embodying my invention. Figs. 2, 3, and 4 represent longitudinal sections thereof, certain parts being in different 20 positions.

Similar letters of reference indicate corresponding parts in the figures.

Referring to the drawings, A designates the 25 stretcher-attaching head of an umbrella-runner, and B designates the tube which depends from said head and encircles the stick of the umbrella, the lower end of said tube being adapted to rest on the catch C of the stick 30 when the umbrella is open, (see Fig. 2,) thus controlling the runner and preventing lowering of the same. Freely encircling said tube is the sleeve D, whose upper portion is adapted to slide on said tube and whose lower 35 portion is adapted to slide on the umbrella-stick. On the exterior of the tube, near the lower portion thereof, is an outturned knurl or shoulder E, and on the interior of the sleeve, near the upper portion thereof, is the inturned 40 wall or shoulder F. Interposed between said tube and sleeve is the coil-spring G, which is seated on the shoulder E and adapted to be engaged by the shoulder F, whereby when the sleeve is depressed said spring is compressed, 45 so as to subsequently return the sleeve to its normal position. The wall of the sleeve is also inturned, say, below its central portion, forming the shoulder H, which is adapted to engage the projecting face of the catch C and

force the latter into the stick, whereby the 50 lower edge of the tube clears said catch and permits the runner to descend the stick. It will be seen that said shoulder H is integral with the sleeve, it being formed by inwardly crimping the metal or material of the same, 55 preferably sheet metal, admitting of the formation of the sleeve jointless from end to end.

When the umbrella is to be closed, the operation is as follows: The sleeve is grasped and lowered, whereby the shoulder H contacts with the upper edge of the projecting portion of the catch C and presses inwardly against the same, (see Fig. 3,) thus forcing the catch partially into the stick, when as the adjacent side edge of said catch is rounded or 65 inclined and the lower end of the tube presses against said edge the catch is fully forced into the stick, thus removing the catch from the path of the tube, whereby the runner may continue its descent, which occurring as shown 70 in Fig. 4 the umbrella may be closed as usual. When the runner is let go, the spring G expands and restores the sleeve upwardly to its normal position. When the runner is raised to open the umbrella, it rides on the 75 stick, as usual, and passes over the catch C, the latter then being pressed into the stick by the contact of the tube B thereagainst until the lower end of the tube clears the top of the 80 catch, when the latter springs out from the stick into the lower portion of the sleeve, when said tube rests on the top of the catch, and so locks the runner, the descent of which is prevented by the projection of the top of the catch across the path of the tube, as will 85 be most apparent in Fig. 2, where, as is evident, the catch is inclosed and concealed by the sleeve, the fingers are removed from contact with said catch, and the disengaging action of the latter is outwardly effected by the 90 downward motion of the sleeve in the manner hereinbefore stated.

The lower end of the sleeve is provided with the cup J for receiving the tips of the umbrella and firmly holding the same in the 95 closed position of the umbrella.

Various changes may be made in the details of construction shown without departing from

the general spirit of my invention, and I do not, therefore, desire to be limited in each case to the same.

Having thus described my invention, what 5 I claim as new, and desire to secure by Letters Patent, is—

1. In an umbrella-runner, a runner-tube provided with an outturned shoulder above the bottom thereof, a sleeve slidable on said 10 tube and provided with an inturned shoulder at its upper end, a spring interposed between said tube and sleeve between said shoulders and an inwardly-projecting shoulder on the interior of said sleeve below said spring.

15 2. In an umbrella-runner, a runner-tube, a sleeve slidable on said tube, an outwardly-extending shoulder on said tube, an inwardly-extending shoulder on said sleeve, a spring

interposed between said tube and sleeve and between said shoulders and an inwardly-extending shoulder on the interior of said sleeve below the shoulder of said tube. 20

3. In an umbrella-runner, a runner-tube, a sleeve slidable on said tube, an outwardly-extending shoulder on said tube, an inwardly-extending shoulder on said sleeve, a spring interposed between said tube and sleeve and between said shoulders and an inwardly-extending shoulder on the interior of said sleeve below the shoulder of said tube, said shoulder being composed of an integral portion of the wall of said sleeve. 25 30

WILLIAM H. GASKILL.
